UNITED STATES PATENT OFFICE.

JULIUS WEINBERGER, OF NEW YORK, N. Y., ASSIGNOR TO RADIO CORPORATION OF AMERICA, A CORPORATION OF DELAWARE.

BROADCAST RECEIVING SYSTEM.

Application filed April 19, 1927. Serial No. 184,881.

This invention relates to the art of broadcast receiving systems and deals more specifically with a receiver designed for use in connection with the usual broadcasting frequencies, or alternatively for use in connection with the reception of wired radio programs.

The operating frequencies used in connection with wired radio are roughly within the range of 50 to 150 kilo-cycles, whereas the present broadcasting band extends from 500 to 1500 kilo-cycles.

It is, therefore, an object of this invention to provide a single instrumentality for receiving signals in the form of broadcast speech or music either at the broadcast frequencies, or for receiving programs at the frequencies used in connection with wired radio.

The manner in which I carry out this invention will be readily apparent to those skilled in the art from the following description, taken in connection with the accompanying drawing in which, the single figure is a diagrammatic representation of a system embodying my invention.

Referring in detail to the drawing, a conventional superheterodyne receiver is shown diagrammatically, which briefly consists of the following apparatus. The antenna 11 and ground connection 12 are connected to the radio frequency amplifier, which is in turn connected to the radio frequency detector. The local oscillator is connected between these two members. The intermediate frequency amplifier, detector, and audio frequency amplifier are shown diagrammatically, and to this group of apparatus is connected the loud speaker. A double-pole, double-throw switch 13 is connected to the intermediate frequency amplifier and is adapted to make contact selectively, either with the radio frequency detector, or with the contacts 14 and 15 which lead to the wired radio line. The intermediate frequency amplifier of the superheterodyne is adjusted to the frequency at which the wired radio line is operated.

It will thus be seen that in the event that it is desired to use the set as a receiver for broadcast signals the switch 13 is thrown to

the left into contact with the radio frequency detector, whereupon the apparatus functions purely as a superheterodyne receiver. On the other hand, if it is desired to receive a wired radio program, it is merely necessary to throw the switch 13 to the right as shown in the figure, whereby the wired radio signals are fed directly to the intermediate frequency amplifier and detector and subsequently to the audio frequency amplifier and loud speaker.

Obviously the changeover switch 13 may be wired in such a way as to light the filaments and close the plate circuits of the radio frequency portion of the equipment, when thrown to the left, or also to perform other switching operations incident to the use of a radio receiver.

I claim as my invention:

1. In combination a radio receiver of the superheterodyne type having an intermediate frequency amplifier, a wired radio receiving line, and means selectively to connect said line to said amplifier. 70
2. In combination a radio receiver of the superheterodyne type having an intermediate frequency amplifier, a separate source of signal oscillations operating at a frequency equal to the frequency of said amplifier, and means selectively to connect said source to said amplifier. 75
3. In combination a radio receiver having an amplifier stage operating at super-audible frequencies, an amplifier operating at radio frequencies, a line conducting signal oscillation at super-audible frequencies, and means selectively to connect said second mentioned amplifier or said line to said first mentioned amplifier, whereby broadcast or wired radio programs may be received on the same apparatus. 85
4. In combination, means for collecting space radiated signal energy, a superheterodyne receiver having an intermediate frequency amplifier coupled thereto, a wired radio line, and means for selectively connecting said line to said amplifier and simultaneously disconnecting said collecting means therefrom. 95

JULIUS WEINBERGER.
